Attorney, Agent, or Firm—Michael A. Catania[73] Assignee: **Callaway Golf Company**, Carlsbad, Calif.[57] **CLAIM**

The ornamental design for the stress enervating sleeve for golf club, as shown and described.

DESCRIPTION

FIG. 1 is a perspective view of the stress enervating sleeve;
FIG. 2 is a top plan view thereof;
FIG. 3 is a front view thereof;
FIG. 4 is a rear view thereof;
FIG. 5 is a toe end view thereof;
FIG. 6 is a side plan thereof;
FIG. 7 is a heel end view thereof;
FIG. 8 is an opposite side view of FIG. 6; and,
FIG. 9 is a reduced top perspective view thereof, the broken line showing of the driver head is for illustrative purposes only and forms no part of the claimed design.
